UNITED STATES PATENT OFFICE.

DAVID CONLAN, JR., OF BROOKLYN, NEW YORK.

BINDER.

Application filed June 9, 1922. Serial No. 566,951.

To all whom it may concern:

Be it known that I, DAVID CONLAN, Jr., a citizen of the United States, and a resident of Brooklyn, Kings County, and 5 State of New York, have invented certain new and useful Improvements in Binders, of which the following is a specification.

The present invention relates to the classification and collection of loose sheets.

10 Particular objects of the invention are to provide a simple and practical form of binder which will hold only the sheets or leaves belonging in that binder, and to enable the ready classification of the leaves 15 and the identification of the same with the binders in which they belong.

Other objects and the various novel features of construction, combinations and relations of parts by which these objects are 20 accomplished will appear as the specification proceeds.

In the accompanying drawing forming part of this specification I have illustrated but one of the many possible embodiments 25 of the invention, it being understood that the structure may be modified and changed in various respects without departure from the true spirit and scope of the invention as hereinafter defined and claimed.

30 Figure 1 in the drawing referred to is a broken perspective view of one of the binders.

Figure 2 is a plan view of the same with the top cover removed and the back shown 35 in section.

Figure 3 is a cross sectional view looking toward the back of the binder.

Figure 4 is a fragmentary view of a portion of one of the sheets with its identifying characters and the binder posts with 40 which it is to be associated.

Figure 5 is a broken longitudinal sectional view of the binder with the leaves engaged therein.

45 Figure 6 is a fragmentary plan view showing how the binder pins serve as the identifying characters for the binder.

Figure 7 is a perspective view illustrating a method of building up the binder posts.

50 Figure 8 is a fragmentary view of one of the sheets showing how the identifying characters may be formed in a reinforcing strip attached to the sheet.

The binder illustrated is in the nature of 55 a folder having top and bottom covers 10, 11 connected by a back 12.

The leaves or sheets, some of which are shown at 13 in Figure 5, are held in the binder on posts or pins 14 which are distinguishably constructed to serve both as 60 identifying characters for the binder and as selective holders for only correspondingly identified sheets.

In the present disclosure the identification or individualization is effected by constructing the posts with their end faces and shanks shaped to form numbers, but it will be realized that letters or other distinguishing outlines might be used.

In order that the binder may be given a desired designation I have illustrated one way in which the character posts may be removably and interchangeably mounted therein, by having flat bases 15 adapted to be secured within a channel provided by a strip 16 secured to the bottom cover and having an inturned flange 17 at the back and correspondingly inturned lugs 18 at the front. Figure 2 shows how with this construction the bases of the number posts are slipped into position between spacing lugs 19 struck up from the holding plate and how the front lugs are then bent up and over the bases to clamp them in place. This construction enables the numbers to be changed at any time by simply turning back the lugs or tongues far enough to release the bases.

The base plate may be in the form of a sheet metal strip secured to the back cover by means of integrally formed tongues 20 and the same is shown as constructed with integrally formed tabs or prongs 21 adapted to be passed up through the front cover and bent over to hold said cover down on the 95 posts and thereby secure the papers on the binder posts.

To make the binders plainly identified, the ends of the character posts are preferably exposed through the top cover as by forming said cover with a window or opening such as indicated at 22 in Figures 5 and 6, which window or windows may be reinforced, if found desirable, by strips 23 extending thereacross but so arranged as not to materially obscure the numbers.

The sheets are provided with perforations 24 shaped to fit the numbers or other distinguishing characters of the binder posts. Thus the sheets to fit in the binder shown in Figure 2 will be punched with the number 47320 to fit over the corresponding number posts 47320 of the binder and that portion

of the sheet shown in Figure 4 is punched with the number 64 to fit over the corresponding 64 binder posts.

The perforations in the sheets thus serve

5 as a means of identifying the same. These numbers may be cut in any suitable form of press, preferably one of a type that can be readily adjusted to punch different numbers grouped in different relations.

10 Provision may be made for expanding the binder to hold a greater number of sheets as by furnishing extra post sections 14^a of the same shape as the main posts and detachably engageable thereon as by providing 15 them with spring pins 25 on their lower ends to fit into sockets 26 in the upper ends of the main posts.

To assist in the proper spacing of the covers spacing sleeves 27 may be slipped on 20 the securing prongs between the covers, as shown particularly in Figures 1 and 3.

If desired, the identifying and filing perforations may be cut in separate strips, such as I have shown at 28 in Figure 8, of thin 25 sheet metal or other suitable reinforcing material, which strips may be attached to the sheets by means of attaching prongs 29 or other fastenings.

This invention, it will be seen, gives to 30 both the holder and the sheet or other element which is to be associated with the holder a definite characterization or means of identification, which in addition to distinguishing and identifying, serves as the 35 means for joining such parts and for insuring the joinder of only those corresponding and therefore properly related parts. The posts are symmetrically related and therefore easily readable and can be readily 40 changed or added to to form different numbers.

By using reinforcements in which the identifying characters are punched the wear 45 of placing the sheets on and removing them from the binder posts is taken by the reinforcements and hence the sheets are not liable to become torn. The reinforcing structure may of course be varied from that shown in Figure 8, one convenient method 50 being to make the same in the form of grommets or tubular rivets, readily attachable to the sheets.

What I claim is:

55 1. In combination, a binder provided with identifying and leaf-securing binder posts, each having a section of alphabetical or numerical significance and thereby providing in their assembly a legend identifying the binder and distinguishing the same by a readable title from other binders, and leaves 60 identified by the same legendary characters in the form of perforations shaped and positioned to correspond with the shapes and positions of the binder posts, whereby said

leaves are given a readable title, identifying 65 and distinguishing the same from leaves intended for other binders and whereby the leaves thus entitled will properly fit only in the binder bearing the corresponding legend or title.

2. The structure of claim 1 in which the posts are detachably and interchangeably held in the binder and are readily changeable for the purpose of altering the identity 70 and changing the title of the binder.

3. The structure of claim 1 in which means are provided for releasably confining the sheets on the binder posts, said means being constructed to enable ready removal of the sheets from the post.

4. In combination, a holder provided with an identifying and sheet-securing post having the outline of a recognized alphabetical or numerical figure and thereby identifying the holder by a readable title and a sheet-like element entitled and identified as belonging and attachable to said holder by a perforation of the size and shape of said post, providing both a readable title for 85 said sheet-like element and a means enabling the engagement of the same over the post of the holder.

5. The structure of claim 4 in which the binder posts have readily added sections by 90 which the binder can be built up to accommodate additional sheets without destroying the recognizable characters of the posts.

6. The structure of claim 4 with means 95 for securing the sheet-like element upon the post of the holder.

7. In combination, a binder having covers and a holder between said covers provided with means for securing the covers closed over the holder, and binder posts removably and interchangeably secured in said holder 100 and each having a distinguishing configuration enabling the changing of the identity of the binder by the shifting of such binder posts.

8. A binder having covers and binder posts held in position between said covers and each forming a definite distinguishable character for the identification of the binder, one of the covers having a window or windows therein exposing the identity of such characters.

9. A binder having a guideway with spacers therein and bendable fingers and binder posts having base portions interchangeably engageable in the guideway between the spacers and adapted to be held by the bendable fingers.

10. The structure of claim 1 with covers for the binder, one having a window or windows exposing the binder posts and therefore disclosing the title of the binder.

11. The structure of claim 4 with a cover for the holder having a window exposing the

post and thereby disclosing the title of the holder even when the cover is closed.

12. The structure of claim 1 in which the entitling and securing perforations are formed through a reinforcement applied to or connected with the sheet-like element. 10

entitling and securing perforations are formed through a reinforcement applied to or connected with the sheet-like element. 10

5 13. The structure of claim 4 in which the

entitling and securing perforation is formed through a reinforcement applied to or connected with the sheet-like element.

In witness whereof, I have hereunto set my hand this 3rd day of June, 1922.

DAVID CONLAN, JR.
